UNITED STATES PATENT OFFICE

170,030

ILLUMINABLE PYLON

Lloyd A. Sauer, Milwaukee, Wis.

Application July 18, 1952, Serial No. 20,662

Term of patent 3½ years

(Cl. D72—1)

To all whom it may concern:

Be it known that I, Lloyd A. Sauer, a citizen of the United States of America, residing at Milwaukee, in the county of Milwaukee and State of Wisconsin, have invented a new, original, and ornamental Design for an Illuminable Pylon, of which the following is a specification, reference being had to the accompanying drawing, forming part thereof.

Figure 1 is a side elevational view of an illuminable pylon, showing my new design.

Fig. 2 is an edge elevational view.

Fig. 3 is a top plan view.

I claim:

The ornamental design for an illuminable pylon, as shown.

LLOYD A. SAUER.
